[57] CLAIM

The ornamental design for a sun visor, as shown and described.

DESCRIPTION

FIG. 1 is a top plan view of a sun visor showing our new design; the bottom plan view being identical thereto;

FIG. 2 is a side elevational view thereof;

FIG. 3 is a side elevational view as seen when worn; and FIG. 4 is a front elevational view in worn position; the broken line showing of a head is for illustrative purposes only.

FIG. 1

FIG. 2

FIG. 3

FIG. 4
